(57) **CLAIM**

The ornamental design for an ultra driver cup, as shown and described.

DESCRIPTION

FIG. 1 is a left side view of the ultra driver cup according to our new design.

FIG. 2 is a front view of the ultra driver cup as shown in FIG. 1.

FIG. 3 is a right side view of the ultra driver cup as shown in FIGS. 1-2.

FIG. 4 is a rear view of the ultra driver cup as shown in FIGS. 1-3.

FIG. 5 is a top view of the ultra driver cup as shown in FIGS. 1-4; and,

FIG. 6 is a bottom view of the ultra driver cup as shown in FIGS. 1-5.

The showing of the broken lines illustrates the environment of the article of the ultra driver cup and forms no part of the claimed design, but are shown to indicate exit holes, fasteners, or attachment features.
